Specification for Design.

Patented Aug. 2, 1921.

Application filed April 4, 1921. Serial No. 458,553. Term of patent 3½ years.

To all whom it may concern:

Be it known that I, SISSAG K. OUZOUN-BOGHOSSIAN, a subject of the Sultan of Turkey, (having declared my intention of becoming a citizen of the United States,) residing at the city of Washington, District of Columbia, have invented a new, original, and ornamental Design for Grilles for Phonograph-Cabinets and Organs, of which the following is a specification, reference being

had to the accompanying drawing, forming part hereof.

The figure is a plan view of a grille for phonograph cabinets and organs, showing my new design.

I claim:

The ornamental design for a grille for phonograph cabinets and organs, as shown.

In testimony whereof I affix my signature,

SISSAG K. OUZOUN-BOGHOSSIAN.
